UNITED STATES PATENT OFFICE.

REINHOLD KRUMMING, OF MILWAUKEE, WISCONSIN.

TEMPORARY BINDER OR LOOSE-SHEET HOLDER.

1,110,444.

Specification of Letters Patent. Patented Sept. 15, 1914.

Application filed December 10, 1913. Serial No. 805,798.

To all whom it may concern:

Be it known that I, REINHOLD KRUMMING, a citizen of the United States, residing at Milwaukee, Wisconsin, have invented certain 5 new and useful Improvements in Temporary Binders or Loose-Sheet Holders, of which the following is a specification.

This invention relates to improvements in temporary binders or loose sheet holders.

10 The main objects of this invention are: First, to provide in a temporary binder or loose sheet holder an improved ratchet adjusting mechanism. Second, to provide an improved temporary binder or loose sheet 15 holder of the post type which may be very quickly and easily adjusted to secure the leaves or to permit the removal thereof. Third, to provide in a temporary binder or loose sheet holder in which the binder parts 20 are made mainly of metal covered with flexible fabric, an improved means of securing the fabric. Fourth, to provide an improved temporary binder or loose sheet holder which is very economical and simple in 25 structure, and at the same time very durable.

Further objects, and objects relating to structural details, will definitely appear from the detailed description to follow.

30 I accomplish the objects of my invention by the devices and means described in the following specification.

The invention is clearly defined and pointed out in the claims.

35 A structure which is a preferred embodiment of my invention is clearly illustrated in the accompanying drawing, forming a part of this specification, in which

Figure I is a detail inside view with the 40 covers extended. Fig. II is a detail section through the adjusting mechanism on a line corresponding to line 2—2 of Fig. I. Fig. III is a detail section on a line corresponding to line 3—3 of Fig. I. Fig. IV is a detail section of the adjusting mechanism on a line corresponding to line 4—4 of Fig. II. Fig. V is a perspective view of the spring 45 pawls and their operating lever. Fig. VI is a horizontal section on a line corresponding to line 6—6 of Fig. II. Fig. VII is a plan view of the blank from which the support member is formed. Fig. VIII is a plan view of one of the members 29.

In the drawing similar reference characters refer to similar parts throughout the several views, and the sectional views are

taken looking in the direction of the little arrows at the ends of the section lines.

Referring to the drawing, the structure illustrated is provided with a pair of covers 60 1 and 2. The binding members 3 and 4 are secured to the covers 1 and 2 respectively by means of the flexible hinge connection 5. The binding members 3 and 4 are provided with inwardly projecting over-lapping members or portions 6 and 7 respectively which form the back of the binder. The binding members are provided with telescoping posts 8 and 9 respectively. The binding members are, in practice, formed of sheet 70 metal with a suitable covering 10 of fabric or leather as may be desired. The binding member 4 is provided with double ratchet members 11 mounted at each end thereof.

Mounted at the ends of the binding member 3 to receive the ratchet members 11 are housing-like supports 12 formed of sheet metal blanks 13, shown in Fig. VII. These sheet metal blanks 13 are folded into rectangular housings as shown, the folding lines 80 being indicated by dotted lines. The side walls of the supports are shouldered at 14, while the lower ends of the end walls are offset inwardly at 15 to these side wall shoulders. The end walls are provided with 85 securing tongues 16 arranged through slots 17 in the member 3 and folded against the outer side thereof, as shown in Fig. II, thus rigidly mounting the members 12 upon the binding member 3.

90 The spring pawls 18 and 19 are provided with shoulders 20 at their lower ends and are arranged in the support with their lower ends between the shoulders 14 of the side walls and the offsets 15 of said end walls, the upper edges of their shoulders 20 engaging the lower edges of the side walls, see Fig. VI. The springs are thus supported within the supports 12 with their upper ends free to coact with the teeth of 95 the ratchet members 11. The upper ends of the springs are turned inwardly to provide engaging portions 21. The end wall of the support having free edge is cut away at 22 to provide a slot for the lever 23. The 100 lever 23 is arranged through this slot and mounted on the outer side wall of the support by means of the pivot 24. The lever is provided with a cam head 25 disposed between the pawls and having inturned lugs 110 26 and 27 coacting therewith, so that when the lever is swung on its pivot to one posi-

tion the pawls are separated, releasing the ratchet, and when moved to the other position the pawls are free to engage the ratchet. The lever is yieldably retained in both positions by the spring pawls. The pawl 18 is cut away at one side, as at 28, to accommodate the lever.

To facilitate the securing of the flexible covering 10, flexible metal tongues 29 are provided. These metal tongues are slotted at 30 to receive the securing tongues 16 of the members 12, and are supported by these members so as to project outwardly, as shown by dotted line in Fig. IV. The end edges of the covering 10 are folded over these flexible tongues, and the tongues are then folded against the sides of the members 12, thereby effectively securing the covering at this point. With the parts thus arranged, the binder is adjusted to clamp the leaves merely by introducing the ratchet members into the supporting members 12 and pushing the same down to clamping position, the levers being thrown into the position shown in Fig. II, to allow the pawls to act. To release the same the levers are thrown down, which releases the pawls, and the ratchet members can then be freely withdrawn. The levers are arranged through the front sides of the members 12 so as to be conveniently grasped and, at the same time, are entirely out of the way and are not likely to be accidentally shifted from one position to another.

I have illustrated and described my improved binder in detail in a simple and effective embodiment. I have not attempted to illustrate or describe certain modifications which I contemplate, as I believe the disclosure made will enable those skilled in the art to which this invention relates to embody or adapt the same as may be desired.

I desire to be understood as claiming my improvements specifically in the form illustrated, as well as broadly within the scope of the appended claims.

Having thus described my invention, what I claim as new and desire to secure by Letters Patent, is:

1. In a binder, the combination of a pair of binding members, a double ratchet member mounted on one of said binding members, a support mounted on the other binding member to receive said ratchet member, said support being formed of sheet metal folded into a rectangular housing, the lower ends of its side walls being shouldered at each edge, the lower ends of its end walls being offset inwardly to said side wall shoulders and provided with securing tongues arranged through slots in said binding member, the end wall having the free edge being cut away at its free edge to provide a lever slot, a pair of spring pawls having shoul-

ders at their lower ends arranged in said support with their lower ends between the shoulders of its side walls and the offsets of its said end walls and with the upper edges of their shoulders engaging the lower edges of said side walls, and a pawl lever arranged through said lever slot in said support and pivoted on one side thereof, said lever being provided with a cam having laterally projecting pawl engaging lugs disposed between said pawls to coact therewith, the pawl on the lever side being cut away at one edge to accommodate the lever.

2. In a binder, the combination of a pair of binding members, a double ratchet member mounted on one of said binding members, a support mounted on the other binding member to receive said ratchet member, said support being formed of sheet metal folded into a rectangular housing, the lower ends of its side walls being shouldered at each edge, the lower ends of its end walls being offset inwardly to said side wall shoulders and provided with securing tongues arranged through slots in said binding member, a pair of spring pawls having shoulders at their lower ends arranged in said support with their lower ends between the shoulders of its side walls and the offsets of its said end walls and with the upper edges of their shoulders engaging the lower edges of said side walls, and a pawl lever pivoted within said support.

3. In a binder, the combination of a pair of binding members, a double ratchet member mounted on one of said binding members, a support mounted on the other binding member to receive said ratchet member, said support being formed of sheet metal folded into a rectangular housing, the lower ends of its side walls being shouldered at each edge, the lower ends of its end walls being offset inwardly to said side wall shoulders, the end wall having the free edge being cut away at its free edge to provide a lever slot, a pair of spring pawls having shoulders at their lower ends arranged in said support with their lower ends between the shoulders of its side walls and the offsets of its said end walls and with the upper edges of their shoulders engaging the lower edges of said side walls, and a pawl lever arranged through said lever slot in said support and pivoted on one side thereof, said lever being provided with a cam having laterally projecting pawl engaging lugs disposed between said pawls to coact therewith, the pawl on the lever side being cut away at one edge to accommodate the lever.

4. In a binder, the combination of a pair of binding members, a double ratchet member mounted on one of said binding members, a support mounted on the other binding member to receive said ratchet member, said support being formed of sheet metal folded into a rectangular housing, the lower

ends of its side walls being shouldered at each edge, the lower ends of its end walls being offset inwardly to said side wall shoulders, a pair of spring pawls having shoulders at their lower ends arranged in said support with their lower ends between the shoulders of its side walls and the offsets of its said end walls and with the upper edges of their shoulders engaging the lower edges of said 10 side walls, and a pawl lever pivoted within said support.

5. In a binder, the combination of a pair of binding members, a ratchet member mounted on one of said binding members, a support mounted on the other binding member, said support being formed of sheet metal, the lower ends of its side walls being shouldered, the lower end of one end wall being offset inwardly to said side wall shoulder, 15 one wall being cut away at its free edge to provide a lever slot, a spring pawl having shoulders at its lower end arranged in said support with its lower end between the shoulder of the side walls and the offset of 20 the said end wall and with the upper edge of its shoulders engaging the lower edges of said side walls, and a pivoted pawl release lever arranged through said lever slot in said support.

25 6. In a binder, the combination of a pair of binding members, a ratchet member mounted on one of said binding members, a support mounted on the other binding member, said support being formed of sheet 30 metal, the lower ends of its side walls being shouldered, the lower end of one end wall being offset inwardly to said side wall shoulder, a spring pawl having shoulders at its 35 lower end arranged in said support with its lower end between the shoulder of the side walls and the offset of the said end wall and with the upper edge of its shoulders engaging the lower edges of said side walls, and a pivoted pawl release lever within said 40 support.

45 7. In a binder, the combination of a pair of binding members, a ratchet member mounted on one of said binding members, a support mounted on the other binding member, said support being formed of sheet metal, the lower ends of its side walls being shouldered, the lower end of one end wall being offset inwardly to said side wall shoulder, a spring pawl arranged in said support 50 with its lower end between the shoulder of the side walls and the offset of the said end wall, and a pivoted pawl release lever.

55 8. In a binder, the combination of a pair of binding members, a double ratchet member mounted on one of said binding members, a support mounted on the other binding member to receive said ratchet member, said support being formed of sheet metal folded into a rectangular housing, the end 60 wall having the free edge being cut away at

its free edge to provide a lever slot, a pair of spring pawls mounted within said support, and a pawl lever arranged through said lever slot in said support and pivoted on one side thereof, said lever being provided 70 with a cam having laterally projecting pawl engaging lugs disposed between said pawls to coact therewith, the pawl on the lever side being cut away at one edge to accommodate the lever.

75 9. In a binder, the combination of a pair of binding members, a ratchet member mounted on one of said binding members, a support mounted on the other binding member to receive said ratchet member, said support being formed of sheet metal folded into a rectangular housing, the end wall having the free edge being cut away at its free edge to provide a lever slot, a spring pawl mounted within said support, and a pawl lever arranged through said lever slot in said support and pivoted on one side thereof.

80 10. In a binder, the combination of a pair of binding members, a double ratchet member mounted on one of said binding members, a housing-like support mounted on the other binding member to receive said ratchet member, said support having a longitudinal lever slot therein, a pair of spring pawls mounted within said support, and a lever 90 arranged through said lever slot in said support and pivoted therein, said lever being provided with a cam disposed between said pawls to coact therewith, said lever being yieldingly retained in both its pawl engaging and releasing positions by said pawls.

95 11. In a binder, the combination of a pair of binding members, a double ratchet member mounted on one of said binding members, a support mounted on the other binding member, a pair of spring pawls mounted on said support, and a lever pivoted on said support and provided with a cam disposed between said pawls to coact therewith, said lever being yieldingly retained in both its 105 pawl engaging and releasing positions by said pawls.

10. In a binder, the combination of a pair of binding members, a ratchet member mounted on one of said binding members, a housing-like support mounted on the other binding member to receive said ratchet member, said support having a longitudinal lever slot in the front wall thereof, a spring pawl mounted within said support, and a pawl 110 release lever arranged through said lever slot in said support and pivoted therein.

115 12. In a binder, the combination of a pair of binding members, coacting telescoping post members on said binding members, a pair of double ratchet members mounted at the ends of one of said binding members, a pair of supports mounted at the ends of the other binding member to receive said ratchet members, said supports being formed of 120 sheet metal, the lower ends of the supports being shouldered, the lower end of one end wall being offset inwardly to said side wall shoulder, a spring pawl having shoulders at its lower end arranged in said support with its lower end between the shoulder of the side walls and the offset of the said end wall, and a pivoted pawl release lever.

125 13. In a binder, the combination of a pair of binding members, coacting telescoping post members on said binding members, a pair of double ratchet members mounted at the ends of one of said binding members, a pair of supports mounted at the ends of the other binding member to receive said ratchet members, said supports being formed of 130 sheet metal, the lower ends of the supports being shouldered, the lower end of one end wall being offset inwardly to said side wall shoulder, a spring pawl having shoulders at its lower end arranged in said support with its lower end between the shoulder of the side walls and the offset of the said end wall, and a pivoted pawl release lever.

sheet metal folded into rectangular housings, the end walls having the free edges being at the front and being cut away to provide lever slots, pairs of spring pawls mounted in said supports, and levers pivoted within said supports and arranged through said slots in said housings, said levers being provided with cams disposed between said pawls to coact therewith, the pawls on the lever sides being cut away at one edge to accommodate the levers.

14. In a binder, the combination of a pair of binding members, coacting telescoping post members on said binding members, a pair of double ratchet members mounted at the ends of one of said binding members, a pair of supports mounted at the ends of the other binding member to receive said ratchet members, said supports being formed of sheet metal folded into rectangular housings, the end walls having the free edges being at the front and being cut away to provide lever slots, pairs of spring pawls mounted in said supports, and levers pivoted within said supports and arranged through said slots in said housings, said levers being provided with cams disposed between said pawls to coact therewith.

15. In a binder, the combination of a pair of binding members, coacting telescoping post members on said binding members, a pair of ratchet members mounted at the ends of one of said binding members, a pair of housing-like supports mounted at the ends of the other binding member to receive said ratchet members, said supports having lever slots in their front walls, spring pawls mounted in said supports, and pawl release levers pivoted within said supports and arranged through said slots in said housings, said levers being yieldingly supported in their pawl releasing and engaging positions by said pawls.

16. In a binder, the combination of a pair of binding members, coacting telescoping post members on said binding members, a

pair of double ratchet members mounted at the ends of one of said binding members, a pair of supports mounted at the ends of the other binding member, pairs of spring pawls mounted on said supports, and levers pivoted on said supports and provided with cams disposed between said pawls to coact therewith, said levers being yieldingly retained in their pawl releasing and engaging positions by said pawls.

17. In a binder, the combination of a binding member, a binding means comprising members mounted at the ends of said binding member and having securing tongues at their bases arranged through slots in said binding member; a covering of flexible material for said binding member, flexible metal tongues slotted to receive said securing tongues and secured to said binding members thereby to project at the ends thereof, the edges of said flexible covering being folded over said flexible tongues, the flexible tongues being folded against the sides of said members mounted on said binding members, whereby the edges of the covering are secured.

18. In a binder, the combination of a binding member, a binding means comprising members mounted at the ends of said binding member, a covering of flexible material for said binding member, flexible metal tongues secured to said binding member to project at the ends thereof, the edges of said flexible covering being folded over said flexible tongues, the flexible tongues being folded against the sides of said members mounted on said binding member, whereby the edges of the covering are secured.

In witness whereof, I have hereunto set my hand and seal in the presence of two witnesses.

REINHOLD KRUMMING. [L.S.]
